CLOSED CAR SIGNAL

Filed Dec. 10, 1924

Patented Sept. 21, 1926.

UNITED STATES PATENT OFFICE.

EUGENE T. McCARTY, OF CHICAGO, ILLINOIS.

CLOSED-CAR SIGNAL.

Application filed December 10, 1924. Serial No. 754,902.

During the winter months when the weather is inclement, closed cars of the sedan type and the like are extensively used, and when the front door windows are closed it is impossible for the driver of the car to project his hand outwardly through the window or side of the car for the purpose of giving warning signals to following cars. To obviate this difficulty an improved traffic signal has been invented for attachment upon the frame of the front left hand door of a closed car, said traffic signal being so constructed that the same may be projected from a retracted position on the inner side of the door into a projected indicating position projected from the left hand side of the vehicle.

It is an object of this invention to provide an improved traffic signal for use in vehicles of the closed type.

It is also an object of this invention to provide a traffic signal adapted to be manually operated from the interior of a closed vehicle, said traffic signal being adapted to be projected outwardly through the door positioned at the left of the driver's seat.

It is another object of this invention to provide an improved closed car traffic signal adapted to be projected through one of the windows of a closed car to afford a signal to following cars, said signal being so constructed that the same may be retracted so that the major portion of the device may be swung at an angle into and out of the way position on the inner side of the door.

It is still another object of this invention to provide a closed car traffic signal adapted to be projected through a door of a closed vehicle by manually swinging the inner major portion of the device into alignment with the outer minor portion of the device thereby moving a spring controlled lever or latch bar into engagement with the minor portion of the device to hold the two portions of the device in alignment, whereby the device may be slidably projected out through the vehicle door to afford a traffic signal.

It is an important object of this invention to provide a closed car traffic signal adapted to be projected through a closed door of

a vehicle to afford a traffic signal without requiring any portion of the closed vehicle to be opened.

Other and further important objects of this invention will be apparent from the disclosures in the specification and the accompanying drawings.

This invention (in a preferred form) is illustrated in the drawings and hereinafter more fully described.

On the drawings:

Figure 1 is a fragmentary elevation of the inner side of a closed vehicle door equipped with a closed car traffic signal embodying the principles of this invention.

Figure 2 is a top plan view of the device taken on line II—II of Figure 1 showing the signal device in projected signal position in full lines and in retracted position in dotted lines.

Figure 3 is an enlarged fragmentary detail section taken on line III—III of Figure 2 with parts shown in elevation.

Figure 4 is an enlarged transverse detail section taken on line IV—IV of Figure 3.

Figure 5 is an enlarged fragmentary view taken on line V—V of Figure 2 when the signal device is in retracted position as shown in dotted lines.

As shown on the drawings:

The reference numeral 1 indicates the front left hand door or driver's door of a closed motor vehicle as ordinarily provided with a glass window pane 2, the upper margin of which is provided with a recess or notch 3 as illustrated in Figure 1. Secured by means of a retaining bolt 4 or other suitable means to the upper rail 5 of the window frame portion of the door are the upturned flanges 6 which are integrally formed or rigidly secured on the ends of a top plate forming a part of a square cross sectioned guide sleeve 7. Engaged around the outer periphery of the guide sleeve 7 is a rubber washer or guard 8 provided with a peripheral groove which is for receiving the edge of the recess 3 formed in the upper margin of the glass window 2. It will thus be noted that when the guide sleeve 7 is mounted in position that the glass window 2 can be raised from its lowered dotted line position

of Figure 1 into the closed position or full line position with the glass forming a tight fit with the rubber washer 8 on the guide sleeve 7. Mounted on the inner side of the top window rail 5 is a spring latch or clip 9 of any desired construction for holding the inner section of the device in a latched retracted position when not in use as hereinabove more fully described.

10 The signal device proper comprises a short outer sleeve section or casing 10 preferably of rectangular cross section, one of the inner side edges of which is pivotally connected by means of a hinge 11 to one side edge of an inner long sleeve section or casing 12 also preferably of rectangular cross section. Mounted in the outer end of the outer casing section 10 is a lamp socket 13 adapted to removably receive an electric bulb 14. Attached to one terminal of the socket 13 is one end of an insulated wire 15 which is conducted through the outer casing section 10 and through the inner casing section 12. The wire 15 is conducted out through an aperture in the bottom of the inner casing section 12 and may be connected with the lighting circuit of the machine. Connected to the other terminal of the lamp socket 13 is an insulated wire 16 which projects into a switch block 17 of insulating material. Mounted within a recess in the switch block 17 is a coiled spring 18 which serves to hold a switch terminal member 19 (Figure 3) in extended position out of the inner end of the switch block.

15 20 25 30 35

When the casing sections 10 and 12 are in alignment with one another as shown in Figure 3 the switch terminal 19 is projected into frictional engagement with a switch terminal 20 seated within the outer end of a second switch block 21 of insulating material. The switch block 21 is mounted in the outer end of the inner casing section 12 and is in alignment with the switch block 17 when the signal device is in extended position for use as shown in Figure 3. Connected to the switch terminal member 20 is one end of an insulated wire 22 which is conducted through the inner casing section 12 and out of the aperture in the bottom of said casing section to be connected with the lighting circuit of the vehicle. It will of course, be understood that the line wires 15 and 22 of the device may be connected to a separate battery or to any source of electrical energy for the purpose of causing illumination of the signal lamp 14 when desired.

40 45 50 55

Formed on the bottom of the inner end of the inner casing section 12 is a projection or finger piece 23 having pivotally mounting on the upper rear end thereof a closure plate 24 for closing the rear end of the inner casing section 12. The closure plate 24 is resiliently held in closed position by means 60 65

cured to the inner face of the closure plate 24 while the other end is attached to a pin secured within the inner casing section. Integrally formed on the lower margin of the closure plate 24 is a lever or trigger 26 which normally is held out of engagement with the finger piece 23 by means of the coiled spring 25. Pivots connected to the inner face of the closure plate 24 is one end of a link or connecting bar 27 which 70 75 is disposed within the inner casing section 12. The other end of the link 27 is pivotally connected to one end of a latch plate or bar 28. The latch bar 28 is adapted to hold the two casing sections 10 and 12 in 80 aligned position when the signal device is projected. The outer end of the latch bar 28 is rounded or beveled so that the same will ride over the curved corner 29 formed at the open end of a slot 30 which is provided in one side of the front casing section 10 as clearly illustrated in Figure 5. The latch bar 28 is supported on a resilient double-leg support 31 which is engaged around the latch bar within the inner casing section 12 with the legs of said support 85 90 95 100 105 110 115 120 125 130

slidably engaged against the inner face of the bottom wall of the inner casing section 12. The resilient support 31 is adapted to hold the end of the latch bar 28, which projects into the outer casing section 10, in an elevated position above the upper edge of the slot 30 so that the two casing sections can not be pivoted with respect to one another when the device is in its projected position for use. The trigger 26 is provided for the purpose of causing retraction of the link 27 and the latch bar 28 so that when the device is retracted the inner casing section 12 after it is pulled through the guide sleeve may be swung at right angles with respect to the outer casing section 10 alongside of the inner face of the door into latching engagement with the retaining latch member 9 as illustrated in Figure 1.

The operation is as follows:

The improved signal device of this invention is primarily adapted for use in closed motor vehicles of the sedan and coupe types and affords a means whereby an illuminated signal may be readily given when the doors and windows of the vehicle are closed, to indicate that the driver intends to stop the car or make a turn. The signal may be given without opening the door or lowering the window.

Normally the closed car signal device is mounted on the top bar of the frame of the left door of a vehicle and when in such retracted position the inner casing section 12 is swung parallel to the door and is held against movement by the spring latch device 9. The dotted line position of the device illustrated in Figure 2 shows the outer casing section disposed within the sleeve 7

while the inner casing section 12 is swung into a position along side of the inner face of the glass.

When the device is in its normal position 5 as shown in dotted lines in Figure 2 the spring contact member 20 in the switch block 21 is swung out of contact with the contact member 19 of the switch block 17 so that the circuit to the bulb 14 is broken 10 and the light, of course, is extinguished.

To operate the signal to indicate a turn, the operator merely has to engage the finger piece or handle 23 to pull the inner casing section 12 out of latching engagement with 15 the latching member 9 at the same time swinging said inner casing section away from the door into alignment with the outer casing section 10. When this is done the projecting end of the latch bar 28 is 20 moved into engagement with the corner 29 (Fig. 5) thereby causing the latch bar to be depressed so that it will pass through the slot 30 into the front casing section. When the end of the latch bar 28 is 25 depressed the resilient supporting member 31 is also depressed an amount sufficient to permit the lowering of the end of the switch bar. As soon as the switch bar passes through the slot 30 the resilient support 30 acts to move the end of the switch bar against the top of the inner casing section so that it cannot again swing out of said slot 30 but is so positioned that the two 35 casing sections are held in alignment against pivotal movement with respect to one another. At the time the inner casing section is swung into alignment with the outer casing section 10 the projecting contacting member 19 of the switch block 17 engages 40 between the lips of the contact member 20 within the block 21 thereby establishing an electrical circuit to the signal lamp 14. The lamp is thus illuminated and the signal device is slidably projected out through the 45 guide sleeve 7 into the full line position of Figure 2 so that the illuminated lamp will afford a traffic signal to the drivers of the vehicles following advising them that the driver of the particular car intends to make 50 a left turn.

After the signal has been given the signal device may be readily pulled inwardly by the operator until the outer casing section 10 is again positioned within the guide 55 sleeve 7 at which time the operator merely has to press the trigger 26 in order to cause the closure plate 24 to swing outwardly away from the inner end of the inner casing section 12 against the action of the coil 60 spring 25. With a pivotal outward movement of the closure plate 24 the casing link 27 is pulled rearwardly thereby causing the latch bar 28 to be retracted out through the opened end of the front casing section 65 10 thereby permitting the inner casing sec-

tion 12 to be pivoted about the hinge 11 into the dotted line position of Figure 2. The inner casing section may then be pushed into latching engagement with the retaining device 9 to hold the inner casing section 70 latched against pivotal movement.

Simultaneously with the swinging of the inner casing section into the dotted line position of Figure 2 the switch contact members 19 and 20 are automatically 75 separated so that the signal light 14 is extinguished.

It will thus be seen that the improved signal device may be readily operated by the driver of a closed motor vehicle so that 80 turning signals may be given even with the windows of the vehicle in closed position. While the guide sleeve for the signal device is illustrated as being supported beneath the top rail of the door frame it will 85 of course be understood that the door frame top rail may be drilled to hold the guide sleeve 7, thereby obviating the use of the notch 3 in the upper margin of the window 90 glass 2.

I am aware that many changes may be made and numerous details of construction may be varied through a wide range without departing from the principles of this invention, and I therefore do not purpose 95 limiting the patent granted hereon, otherwise than necessitated by the prior art.

I claim as my invention:—

1. A closed car signal comprising pivotally connected slidable casing sections, a 100 signal device carried by said sections, and latch means mounted within the section for holding said sections in alignment with one another when it is desired to slidably project the signal into a position wherein the 105 signal device may be readily seen.

2. The combination with a closed vehicle door and the window glass thereof, of a traffic signal for use on said door comprising a guide sleeve, means for attaching the 110 same to the door frame, a washer carried by said guide sleeve and grooved to receive a notched-out portion of the door window, hingedly connected signal mechanisms 115 slidably disposed in said guide sleeve and adapted to be projected outwardly through said guide sleeve to afford a traffic signal when the door window is closed, and means for retracting said signal mechanisms through the guide sleeve to permit one of 120 said signal mechanisms to be swung in at an angle with respect to the other into an out of the way position along side of the inner side of the door.

3. A closed car signal comprising a tube 125 adapted to be mounted to project through a door of the car, a pair of pivotally connected casing sections normally positioned in the interior of the car, a signal carried by said sections, and means for aligning 130

said sections to permit the same to be projected from the interior of the car outwardly through said tube to display the signal.

5. 4. A closed car signal comprising pivotally connected slidable sections, a signal carried thereby, latch means for holding

said sections in alignment to display the signal, and a trigger mechanism carried by one of said sections to release the latch means.

In testimony whereof I have hereunto subscribed my name.

EUGENE T. McCARTY.
